(Cl. D71—1)

To all whom it may concern:

Be it known that we, Harland M. Poyer and Edgar P. Rhodes, citizens of the United States, residing at Ridge Road, Lewiston, county of Niagara, State of New York, and Greiner Road, Clarence, county of Erie, New York, respectively, have invented a new, original, and ornamental Design for an Airplane, of which the following is a specification, reference being had to the accompanying drawings, forming a part thereof.

Figure 1 is a top plan view of an airplane showing our new design;

Figure 2 is a front elevational view;

Figure 3 is a side elevational view; and

Figure 4 is a rear elevational view thereof.

We claim:

The ornamental design for an airplane, as shown.

HARLAND M. POYER.
